BAR FEEDER

Basil Gray and George Shewan Cleghorn, Sheffield, England, assignors to English Steel Corporation Limited, Vickers Works, Sheffield, England, a British company

Application November 17, 1949, Serial No. 127,970
In Great Britain November 22, 1948

10 Claims. (Cl. 214—1)

1

This invention relates to bar reeling machines and is concerned with the provision of improved feeding means for such machines.

In existing reeling machines, it is the usual practice to place a bar to be reeled in C brackets which are normally provided in line with the mouth of the machine, and then to feed the bar forward into the rolls of the reeling machine by hand. If the leading end of the bar is distorted in any way the rolls may not grip it immediately and the operator then has to give the bar a partial twist or rotation by hand. Immediately the rolls grip the bar, it oscillates and "thrashes" violently and this leads to numerous and serious accidents to the operators of such machines.

A main object of the present invention is to facilitate the feeding operation in a manner which obviates the necessity of the above-mentioned dangerous hand feeding.

According to one aspect of the present invention there is provided feeding means for a bar reeling machine, said means including a yieldable buffer device which is provided for the transmission of pressure therethrough to the trailing end of a bar when the latter is located in the feeding position with its leading or forward end close to the nip between the first rolls of the machine, and which is adapted, on yielding during the application of said pressure, to impart a twist to the bar, the arrangement being such that, if the leading end of the bar cannot readily enter the nip from said feeding position, the buffer device yields and in so doing rotates the bar about its longitudinal axis until the said leading end is brought to a position in which it can readily enter the nip.

According to a more limited aspect of the invention, a buffer or rammer is resiliently carried by a mounting which latter is displaceable for the purpose of applying axial pressure, through said buffer or rammer, to the trailing end of a bar when the latter is located in the feeding position with its leading or forward end within or close to the mouth of the machine, said buffer or rammer being adapted to rotate in said mounting if caused to set-back in relation thereto during the application of said pressure and, in so rotating, to twist the bar to facilitate its entry between the rolls of the machine.

In order that the invention may be clearly understood and readily carried into effect one embodiment thereof will now be described in detail with reference to the accompanying drawings wherein:

Figure 1 is a side elevation, partially broken

away, showing the bar feeding means of the invention together with two C brackets.

Figure 2 is a plan view according to Figure 1.

Figure 3 is a section on the line III—III of Figure 1.

Figure 4 is a section on the line IV—IV of Figure 1.

Figure 5 is a section, to an enlarged scale, on the line V—V of Figure 1, and

Figure 6 is a sectional elevation on the line VI—VI of Figure 2.

Referring now to the drawings, a pair of inwardly directed channel-section tracks 1 are mounted on a raised supporting structure 2 which is arranged to extend in line with the mouth of the bar reeling machine (not shown) and which also carries the normal C brackets 3 towards the end nearer the said mouth. The feeding means proper is carried on a frame 4 mounted on wheels 5 which are arranged to engage and run in the aforesaid tracks 1. Clamps 6 (Figure 5) are provided to lock the wheeled frame 4 in any desired position along the tracks 1 according to the length of the work-pieces to be fed to the reeling machine.

The frame 4 carries a pair of spaced parallel runways or rails 7 which extend parallel to the tracks 1 and which have wheel guards 8 bolted thereon as shown clearly in Figures 3 and 4. The wheels 9 of a carriage 10 are arranged to run on the aforesaid runways or rails 7, the aforesaid wheels 9 being enclosed on their outer faces by the wheel guards 8. A part of the carriage 10 is in the form of a cylindrical casing 11 which is disposed horizontally so that its longitudinal axis will be substantially in line with the longitudinal axis of a bar to be fed into the machine when the bar is supported in the feeding position in the C brackets 3. The end of the cylindrical casing 11 remote from the C brackets is closed by an end plate 12 having a central aperture therethrough. A hollow cylindrical buffer or rammer 13 having an open inner end, is arranged to operate partially within the cylindrical casing 11 and is guided therein by means of an axially extending rod 14 the forward end of which is attached to the outer or forward end of the buffer and the rear end of which extends through and is guided by the aperture in the rear plate 12.

A coil spring 15 is arranged to surround the rod 14 within the casing and buffer and tends to urge the buffer outwardly from the casing. The end of the spring 15 towards the rear of the casing surrounds and is guided by a sleeve-member 11a which projects from the inner face of the

rear plate 12. The inner end of the buffer or rammer is provided with an outwardly extending annular rim 16 which is arranged to abut against an inwardly extending annular rim 17 on the forward end of the casing 11 so as to limit the outward stroke of the buffer. At the outer end of the buffer 13 there is mounted a head 18 in the form of a hardened steel plate the outer face of which is dished or formed with a shallow conical depression having radial teeth 19 there-around. It should, of course, be appreciated that this head may take various alternative forms other than that shown in the drawings. A roller 20 extends radially from the periphery of the buffer 13 adjacent the rear end thereof and, when the buffer is in its forward position as shown in Figure 1, is arranged to engage in the forward end of a helical slot 21 formed in the periphery of the cylindrical casing.

An air cylinder 22 is bolted on the frame 4 so that its longitudinal axis extends parallel to the tracks 1 and a piston 23 attached to a piston rod 24 is arranged to work within the said cylinder. Attached to the outer end of the piston rod 24 is a cross-head 25 the lower surface of which is shaped to engage a slide 26 which latter is bolted to the frame 4 as shown in Figure 4. Extending transversely through the cross-head 25 is a stub axle 27 which rotatably carries a pinion wheel 28 at each end. The pinions 28 are respectively arranged to engage and run on a pair of bottom racks 29 which are bolted to the frame 4. The racks 29 extend, as shown in Figure 1, forwardly from the pinions 28.

Secured to the under-surface of the carriage 10 are a further pair of racks 30 with which the pinions 28 also engage and which extend rearwardly from the pinions 28 when the carriage 10 is in the retracted position as shown in Figure 1. These racks 30 are L-shaped in cross-section and are each respectively positioned in the same vertical plane as the corresponding bottom rack 29. On each side of the cross-head 25 near the top thereof are mounted two rollers 31 which are arranged to run on the upper surfaces of the horizontal arm portions of the racks 30.

Pivotedly mounted at the forward end of the cross-head 25 is a transverse plate 32 carrying a bar support roller 33 at its upper end. The plate 32 can pivot forward to move the support roller 33 out of the way of a thrashing bar end during a feeding operation, and is returned to the upright position by slotted link means 32a when the carriage returns to its position of rest. Secured to the forward end of the wheel guards 8 and in front of the C brackets 3 is a V-shaped bar support 34 which also serves as a front stop. A rear stop 35 for the carriage is also provided across the opposite ends of the wheel guards 8 as shown.

Compressed air can be supplied to the cylinder 22 on either side of the piston 23 in known manner, the supply being normally controlled by hand-operated levers (not shown).

The C brackets 3 are preferably mounted on pivots 3a, as shown, so that they can be swung aside out of the path of the frame 4 when not required for use.

In operation, the position of the frame 4 is first adjusted along the tracks 1 according to the length of bar to be fed into the reeling machine. Then, assuming that the bars are of sufficient length to require the use of C brackets to provide additional support, a bar is placed in these brackets so that the rear end of the bar rests on the sup-

port roller 33 and V-support 34 whilst the forward or leading end of the bar enters the mouth of the machine (not shown) up to the nip of the first rolls in the machine. To this end, the machine mouth may be provided with a conical lead-in tube having its outer end cut-away on a bevel to facilitate the entry of the bar. The pneumatic piston and cylinder arrangement is then operated so that the cross-head 25 moves along its slide 26 to the right as seen in Figures 1 and 2 of the drawings, that is towards the mouth of the machine. This movement of the cross-head causes the pinions 28 to move along the bottom racks 29 and, the latter being fixed, the top racks 30 together with the carriage are thereby caused to move forward at twice the speed of the cross-head. The buffer or rammer 13 is thus brought up against the rear end of the bar so as to exert axial pressure thereon in the feed direction. The conical or dish-shaped buffer head tends to cause the trailing end of the bar to move into the centre of the head. If the bar is gripped between the nip of the rolls as soon as pressure is applied to the trailing end thereof, it will be rapidly drawn away from the carriage and buffer and the pneumatic mechanism can then be operated to reverse the carriage. If, on the other hand, the rolls do not immediately grip the bar, due possibly to some slight distortion, the resistance to feed during the forward movement of the carriage will cause the buffer 13 to set-back and compress the coil spring whilst increasing the end load on the bar. When the buffer is thus set-back, the roller 20 travels along the helical slot 21 so that the buffer is turned about its longitudinal axis simultaneously with the set-back. During this turning motion, the teeth on the buffer head tend to bite into the trailing end of the bar so as to apply a torque or twist thereto. This causes the bar to rotate about its longitudinal axis until the leading end moves into a position in which it can readily pass between the nip of the rolls. Once in this position the rolls operate to draw the bar rapidly away from the carriage which can then be reversed by operating the pneumatic means as aforesaid.

As will be appreciated, the operation of the carriage is not limited to pneumatic means as described and it may obviously alternatively be operated or traversed by hand, mechanical or any other means. Likewise the main spring of the buffer device could be replaced by a piston acting against a cushion of compressed air within the casing or by some other suitable arrangement. The carriage could also, for example, be traversed by a system of chains and pulleys operated by an air cylinder and piston assembly.

We claim:

1. Apparatus for feeding a bar reeling machine comprising means for supporting a bar to be reeled with its leading end close to the mouth of said machine, a displaceably mounted yieldable buffer device arranged, on displacement, to apply axial pressure to the trailing end of said bar, means for displacing said buffer device to apply said pressure, and means associated with said buffer device for operation on set-back of the buffer during said pressure application, to twist said bar about its longitudinal axis.
2. Apparatus for feeding a bar between co-operating rollers of a bar reeling machine comprising means for supporting said bar in a position substantially in line with the nip between said rollers and with its leading end close to the

said nip, a yieldable buffer device movable along a track to apply pressure to the trailing end of said bar, and means for moving said buffer device to apply said pressure, said buffer device being arranged to yield if, on the application of said pressure, the bar cannot readily enter said nip and, on yielding, being adapted to apply positive torque to the trailing end of said bar to twist the latter into a position in which it can readily enter said nip.

3. Apparatus for feeding a bar reeling machine comprising means for supporting a bar to be reeled with its leading end very close to the nip between the first rolls of said machine, a track extending parallel to the feed path of said bar, a buffer resiliently carried by a buffer cylinder mounted on said track for displacement therewith to apply axial pressure, through said buffer, to the trailing end of said bar, means for displacing said buffer cylinder along said track, means for rotating said buffer in its cylinder if the buffer is caused to set-back during the application of said pressure, and means for transmitting said rotary movement of the buffer to the trailing end of said bar to twist the latter about its longitudinal axis.

4. Apparatus as claimed in claim 3 in which said track is in the form of a pair of horizontal rails and said buffer and buffer cylinder form part of a wheeled carriage arranged to run on said rails.

5. Apparatus as claimed in claim 4 further comprising a main supporting structure for said apparatus, tracks carried by said structure, a wheeled frame arranged to run on said tracks and carrying said rails on which said wheeled carriage is mounted and clamping means for securing said wheeled frame in any predetermined position along said main structure tracks depending upon the length of bars to be fed into the machine.

6. Apparatus as claimed in claim 5 further comprising C brackets carried on said main structure and positioned in the direct feed path between said frame and the mouth of the reeling machine to provide additional support for a bar to be reeled.

7. Apparatus as claimed in claim 6 further comprising pneumatic means for displacing said buffer and cylinder carriage along said rails.

50

8. Apparatus as claimed in claim 7 in which said pneumatic means is in the form of an air cylinder and piston arrangement having one part fixed on the said frame and the other part movable relatively thereto and including a pinion and rack arrangement for connecting said relatively movable part to said carriage whereby the latter can be caused to move at twice the speed of said relatively movable part of the pneumatic assembly.

9. Apparatus for feeding a bar reeling machine as claimed in claim 3 further comprising a coil spring arranged within said buffer cylinder to urge said buffer outwardly from the cylinder, a roller extending radially from the periphery of said buffer and engaging in a helical slot in the wall of said cylinder so as to travel along said helical slot on set-back of the buffer and cause the latter to rotate, and a shallow dished head on the buffer having teeth thereon for gripping the trailing end of said bar.

10. Apparatus for feeding a bar reeling machine comprising means for supporting a bar to be reeled with its leading end close to the mouth of the machine, a displaceably mounted yieldable buffer and cylinder device arranged, on displacement, to apply, through said buffer, axial pressure to the trailing end of said bar, means for displacing said buffer and cylinder device to apply said axial pressure, co-acting means provided respectively on said buffer and cylinder to cause the buffer to rotate in the cylinder on set-back and gripping means on the operative face of said buffer arranged to grip said trailing end of the bar so that, if the buffer sets back during the application of said pressure, the bar is simultaneously twisted about its longitudinal axis.
